Patented Dec. 2, 1919.

Inventor

L.M. Blue

Watson E. Coleman

UNITED STATES PATENT OFFICE.

LILLIE M. BLUE, OF CARTHAGE, NORTH CAROLINA.

GUARD.

1,323,443.

Specification of Letters Patent. Patented Dec. 2, 1919.

Application filed September 7, 1918. Serial No. 253,119.

To all whom it may concern:

Be it known that I, LILLIE M. BLUE, a citizen of the United States, residing at Carthage, in the county of Moore and State of North Carolina, have invented certain new and useful Improvements in Guards, of which the following is a specification, reference being had to the accompanying drawings.

10 This invention relates to certain improvements in guards and has relation more particularly to a device of this general character especially designed and adapted for use in connection with a sewing machine and it 15 is the object of the invention to provide a novel and improved guard adapted substantially to incase the band wheel of a sewing machine whereby entanglement of the clothing of the operator or the work with 20 the wheel is avoided and which also prevents such other contact with the band wheel which would result in injury.

It is also an object of the invention to provide a novel and improved guard of this 25 character which substantially entirely incloses the band wheel and wherein said guard comprises relatively movable sections to permit access being had to the band wheel or the band passing therearound without 30 the necessity of entirely removing the guard.

The invention consists in the details of construction and in the combination and arrangement of the several parts of my improved guard whereby certain important 35 advantages are attained and the device is rendered simpler, less expensive and otherwise more convenient and advantageous for use, all as will be hereinafter more fully set 40 forth.

The novel features of the invention will hereinafter be definitely claimed.

In order that my invention may be the better understood, I will now proceed to describe the same with reference to the accompanying drawings, wherein:

Figure 1 is a view in front elevation of a guard constructed in accordance with an embodiment of my invention and in applied 50 position;

Fig. 2 is a view in side elevation of a structure as illustrated in Fig. 1;

Fig. 3 is a view in side elevation of my guard detached, and reverse to that shown 55 in Fig. 2; and

Fig. 4 is a horizontal sectional view taken through the guard as illustrated in Fig. 3.

As disclosed in the accompanying drawings T denotes the table of a sewing machine structure supported at its opposite ends by the side members S and coacting with the side members S in a conventional manner is the frame F disposed longitudinally with the table T. One end portion of the frame F includes the oppositely directed and vertically disposed arms 1 arranged on a predetermined outward curvature, and the outer end portions of said arms 1 are connected by the vertically disposed arms 2. Rotatably supported by the arms 2 and the upper end portion of the lower arm 1 is the band wheel crank 3 for rotating the band wheel B. Operatively engaged with the band wheel crank 4 is a pitman P coacting in a well known manner with the treadle A suitably mounted upon the lower portion of the frame F.

G denotes my improved guard, as herein disclosed, in its entirety and said guard comprises two hingedly connected sections X and Y, the section X being arranged rearwardly of the frame F and the section Y forwardly thereof. Each of the sections X and Y is formed of reticulated fabric of desired mesh with the strands thereof being preferably of wire so that said section may be readily flexed or bent into desired form. It is also preferred that the marginal portions of each of the sections X and Y have secured thereto a binding 5 preferably produced from sheet metal.

The adjacent marginal portions of the sections X and Y are straight and each of said marginal portions is secured to an elongated member or strip 7, of wood or other relatively light material. The members or strips 7 are hingedly connected as at 6 so that said sections X and Y may be moved one relative to the other and which is of particular importance when the guard G is in applied position as one of said sections may be swung independently of the other into a position to permit access to the band wheel B and its concomitant parts without the necessity of entirely removing the guard G from its working position.

The rear section X has its upper and lower ends arranged in the form of a V with the apices outwardly directed and the outer side margin of said section between 110

the ends substantially straight as indicated at 8 and the opposite end portions thereof are adapted to be secured, as indicated at 9, by wire or the like to the lower portions of 5 the arms 1. The section X is flexed or bent transversely into substantially a semicircular form in cross section and the apex portion of the upper end of the section X is suitably anchored as at 10 to the under 10 surface of the table T at a point rearwardly of but in close proximity to the rear opening 11 in the table T through which the band B' passes. The inner marginal portion of the section X is secured adjacent its opposite 15 ends, as indicated at 12 to the upper and lower portions of the arm 2, although, if preferred, the member or strip 7 may be suitably anchored to the arm 2 to the same advantage.

20 The front section Y of the guard G is bent or flexed transversely into such a form as to extend around a forward portion of the band wheel B and the dress guard D coacting therewith. The upper end portion 25 of the section Y is provided with an extension 14 with its top marginal portion arranged on an upward incline toward the outer or free vertical margin of the section Y. The apex portion of the extension 14 is detachably connected, as at 15, by a hook member or the like with the under 30 face of the table T while the lower portion of the outer or free vertical marginal portion of the section Y is similarly connected 35 as at 16 with the lower portion of the dress guard D. By releasing the connections at 15 and 16 the forward section Y may be swung readily into a position to afford access to the band wheel B or the band B' as 40 the occasions of practice may require and particularly when it is desired to throw the band B' onto or off of the band wheel B.

The V formation at the lower end of the section X avoids any obstruction of hindrance being offered to the requisite operation of the treadle A and its coacting pitman P and also provides an arrangement whereby the lower portion of the section X closely approaches the floor or other supporting surface which results in a material 45 advantage in the use of the guard G.

From the foregoing description, it is thought to be obvious that a guard constructed in accordance with my invention is particularly well adapted for use by reason 55 of the convenience and facility with which it may be assembled and operated and it will also be obvious that my invention is susceptible of some change without departing from the principles and spirit thereof and 60 for this reason I do not wish to be understood as limiting myself to the precise arrangement and formation of the several parts herein shown in carrying out my invention in practice as hereinafter claimed. 65

I claim:

1. A guard for a band wheel of a sewing machine comprising two hingedly connected sections, said guard being adapted to be supported by the table and frame of 70 a sewing machine structure, the upper end portion of one of the sections being in V formation with the apex thereof outwardly directed, said apex portion being adapted to be secured to the table of the sewing machine structure.

2. A guard for a band wheel of a sewing machine comprising two hingedly connected sections, said guard being adapted to be supported by the table and frame of 80 a sewing machine structure, the opposite end portions of one of the sections being in V formation with the apices thereof outwardly directed.

3. A guard for a band wheel of a sewing 85 machine comprising two hingedly connected sections, said guard being adapted to be supported by the table and frame of a sewing machine structure, the opposite end portions of one of the sections being in V 90 formation with the apices thereof outwardly directed, the upper apex portion being adapted to be secured to the table of a sewing machine structure.

In testimony whereof I hereunto affix my 95 signature in the presence of two witnesses.

LILLIE M. BLUE.

Witnesses:

JOHN BLUE,
FANNIE MUSE.
